Much Shelist, P.C.

(57) **CLAIM**

The ornamental design for a bottle, as shown and described.

DESCRIPTION

FIG. 1 is a front left side perspective view showing the new design for a bottle;

FIG. 2 is a front right side perspective view thereof;

FIG. 3 is a rear left side perspective view thereof;

FIG. 4 is a rear right side perspective view thereof;

FIG. 5 is a front elevation view thereof, the rear elevation being a mirror image thereof;

FIG. 6 is a left side view thereof, the right side being a mirror image thereof;

FIG. 7 is a top plan view thereof;

FIG. 8 is a bottom plan view thereof;

FIG. 9 is a front left side perspective view showing another new design for the bottle;

FIG. 10 is a front right side perspective view thereof;

FIG. 11 is a rear left side perspective view thereof;

FIG. 12 is a rear right side perspective view thereof;

FIG. 13 is a front elevation view thereof, the rear elevation being a mirror image thereof;

FIG. 14 is a left side view thereof, the right side being a mirror image thereof;

FIG. 15 is a top plan view thereof; and,

FIG. 16 is a bottom plan view thereof.

The broken lines in the drawings showing the bottle illustrate the portions of the bottle that form no part of the claimed design.

1 Claim, 16 Drawing Sheets
